UNITED STATES PATENT OFFICE.

SAMUEL E. SPERRY, OF WOODHAVEN, NEW YORK.

METAL-POT-MOUTHPIECE WIPER.

Application filed December 7, 1925. Serial No. 73,771.

The present invention relates to improvements in typographical machines, and more especially to those of the class shown and described in U. S. Letters Patent to O. 5 Mergenthaler, No. 436,532, granted September 16th, 1890; and it pertains more particularly to the casting mechanism thereof which embodies a metal pot having a mouthpiece which is movable, with the metal pot, into contact with the rear face of the mold to close the mold at the rear, preparatory to the injecting of type metal into the mold for the casting of the type bars or slugs 10 therein.

The primary object of this invention is to provide a novel and improved wiper for the metal pot mouthpiece which is capable of thoroughly and effectively removing any molten type metal or foreign matter that 15 may adhere to the mold-engaging face of the mouthpiece after each casting operation has been performed, thereby insuring a metal tight joint between the rear face of the mold and the metal pot mouthpiece during each 20 casting operation, and the production of more perfect type bars or slugs.

Wipers have been used for such purposes; but such wipers have been unsatisfactory because, among other reasons, they have been 25 operably secured to the machine frame, the mold disk, or to some other component of the machine which is separate from the metal pot and between which component and the metal pot there is relative operating movement or adjustment in consequence of which 30 the operative relationship between the metal pot mouthpiece and the portion of the wiper which cooperates with it was disturbed, with the result, that the wiping action was inefficient or imperfect.

The present invention provides a wiper which is operably secured to the metal pot, so that the movements of the pot about its fulcrum cannot affect the operative relationship between the metal pot mouthpiece and the wiper mechanism, because the wiper is supported by the metal pot and moves therewith, thereby insuring maintenance of the proper operating relationship between 45 the mouthpiece and the portion of the wiper which cooperates with it.

The invention has been illustrated, in its preferred embodiment, in the accompanying drawing, wherein:

Fig. 1 is a fragmental front elevation of

that portion of a line casting machine which includes the metal pot and some of the adjacent elements of the machine, showing the wiper embodying the present invention applied thereto.

Fig. 2 is a fragmental side elevation of the parts shown in Fig. 1 as viewed from the left of said figure, the mold wheel being shown in dotted lines;

Fig. 3 is a detail perspective view of the wiper arm detached from the metal pot; and

Fig. 4 is a detail view of portions of the metal pot and wiper member showing a washer interposed between these elements.

The present invention is applicable generally to the casting mechanisms of line casting machines which employ a mold in which type bars or slugs are cast and a metal pot having a mouthpiece to contact with a face of the mold to close it and to inject type metal into the mold cavity, and the purpose of the invention is to provide an improved wiper which will remove from any part of the mold-engaging face of the metal-pot mouthpiece any molten type metal that may adhere thereto after a casting operation, and thus avoid the accumulation of solidified type metal which, if present on the mold-engaging face of the metal pot 85 mouthpiece, would preclude an accurate metal tight fit between the mouthpiece and the cooperative face of the mold.

In the present instance, 1 represents a portion of the spout of the metal pot 2 of casting mechanism, and this metal pot may be of the type generally used in machines of the class generally shown and described in the patent hereinbefore referred to, it being usually mounted on a shaft 3 so that it may swing forwardly preparatory to a casting operation and recede rearwardly after each cast has been made, and is fitted with a mouthpiece 4, the forward face of which is adapted to move into engagement with and to form a metal-tight fit with the rear face of the mold 5 carried by a mold wheel 6 when the metal pot moves forwardly, the metal pot being swung forwardly to bring the mouthpiece into engagement with the mold and retracted therefrom at appropriate intervals by mechanism which is well known to those skilled in the art. The metal pot mouthpiece has the usual or any suitable orifices 7 through which molten type

metal contained in the metal pot is forced, usually by a pump or plunger, into the cavity of the mold in which the type bar or slug is to be cast. The metal pot and its mouthpiece and the mold and mold wheel may be constructed and operated in the manner usual in machines of this general class.

The wiper forming the subject of the present invention serves to prevent accumulations of type metal on the front mold engaging face of the metal pot mouthpiece and which, if permitted to occur, would preclude a metal-tight fit between the mouthpiece and the mold and would result in leakage and loss of type metal and consequent incomplete filling of the mold, and would produce imperfections in the type bars or slugs.

As shown, it comprises a wiping member 8 which is in the form of a bell crank, this member being pivoted to the lower portion of the front face 9 of the metal pot jacket by means of a pin or stud 10 which is secured to and supported by the metal pot jacket. The long arm 11 of the bell crank 25 is offset intermediate its ends, as indicated at 12, so that its outer end will normally be positioned approximately in a vertical plane which substantially coincides with the mold-engaging face of the mouthpiece 4. A wiping medium or pad 13 is secured to the rear or inner face of the outer end of the arm 11. This wiping medium or pad may be formed of any suitable wiping material such as felt, fabric, asbestos, or the like, and the 30 wiper is so positioned and pivoted as to cause the wiping medium or pad to engage and traverse the mold engaging face of the mouthpiece when the wiping member is swung about its pivot or fulcrum.

In order to insure firm but yielding engagement of the wiper medium or pad 13 with the mold-engaging face of the mouthpiece, a helical spring 14 is positioned on the stud 10 which is suitably elongated for 45 the purpose, and one end of this spring presses against the washer 15, which is mounted on the stud and held in position thereon by a cotter pin 16 or other suitable securing device; while the inner end of the 50 spring applies pressure against the pivoted portion of the wiper member. The rear face of this portion of the wiper member has a flat portion which movably bears against the flat front surface face 9 of the metal pot jacket, whereby the wiper member is guided to travel in a given vertical plane which is parallel to the mold-engaging face of the mouthpiece. If preferred, a flat bearing-washer 9^a, shown in Fig. 4, may be interposed between the front face of the metal pot and the adjacent face of the wiper member.

The wiper member 8 has a relatively short arm 17 which extends from its pivoted portion and this arm is pivotally connected

at 18 to the upper end of a link 19. The lower end of the link 19 is pivotally connected at 20, to an actuating arm 21. It has been found that the operations of the usual space band lever 22 commonly used in machines of this class takes place at such times that this space band lever may be utilized as the actuating means for the wiper. The actuating arm 21 may, therefore, be formed as an integral extension of the usual space band lever, or, if preferred, it may be formed as a separate part and then rigidly secured to the fulcrum sleeve of the space band lever in any suitable manner, the space band lever being fulcrumed to the frame of the machine in the usual way, as indicated at 23 and actuated by the usual power mechanism.

In operation, after the slug has been cast the metal pot recedes rearwardly, thereby disengaging the mouthpiece from the mold, after which the space band lever moves about its fulcrum to perform functions well understood by those familiar with machines of this class. As the space band lever swings about its fulcrum 23, the arm 21 which swings therewith, acts through the link 19 to impart a swinging movement to the wiper member 8. During this movement of the wiper member, its wiping pad traverses the mold-engaging face of the metal pot and thereby removes any molten metal or foreign matter that may have adhered to this face; thereby insuring a smooth, clean face for engaging the mold during the next casting operation.

During each cycle of operation of the casting machine, the space band lever moves to the position indicated by dotted lines in Fig. 1 and then returns to its normal position, as indicated in full lines, thereby causing the wiper to move first to the right across the mouthpiece to the position indicated by the dotted lines, and then back to the left into the position indicated in full lines in Fig. 1. In this position the wiping pad carried by the wiping arm is beyond the mouthpiece, thus permitting unobstructed engagement of the mouthpiece with the mold. The connections between the components of the wiper operating mechanism are sufficiently flexible to permit the movements of the metal pot to and from casting position, the location of the connection 20 near the pivotal axis of the metal pot moreover requiring movement substantially of only the upper portion of the link 19 to compensate for the movements of the metal pot.

The wiper when constructed substantially as shown, is capable of being accommodated in the space available in machines of this class between the front of the metal pot and the mold wheel, and the range of motion of the wiper member in performing its wiping operations is such that the upper or wiping

end of this member may operate within the usual rearwardly-projecting rim of the mold wheel, without interference by or with the mold wheel.

5 I claim as my invention:—

1. In a line casting machine, the combination of a metal pot pivoted to swing its metal injecting mouthpiece to and from contact with the mold, an actuating arm extending into proximity to the pivotal axis of the metal pot, a wiper arm pivotally mounted on the metal pot having a wiping portion arranged to traverse the mouthpiece thereof, and a link pivotally connecting the 10 wiper arm to said actuating arm and operative to swing the wiper arm to and fro across the metal pot mouthpiece.

15 2. In a line casting machine, the combina-

tion with a metal pot movable to carry the metal injecting mouthpiece thereof to and from contact with the mold, and a pivoted space-band lever, of a wiper arm pivotally mounted on the metal pot to move therewith and having a wiping portion arranged to traverse the mouthpiece thereof, an actuating arm connected to the space-band lever to swing in unison therewith and projecting from its pivot, and a link connecting said actuating arm to the wiper arm and operative to swing the latter to and fro across the mouthpiece of the metal pot immediately following each casting operation.

In testimony whereof I have hereunto set my hand.

SAMUEL E. SPERRY.
